UNITED STATES PATENT OFFICE.

ADAM HEIM, OF LIBERTY, INDIANA.

REEL.

1,214,031.

Specification of Letters Patent. Patented Jan. 30, 1917.

Application filed April 11, 1916. Serial No. 90,481.

To all whom it may concern:

Be it known that I, ADAM HEIM, a citizen of the United States, residing at Liberty, Indiana, have invented a new and useful Improvement in Reels, of which the following is a specification.

My invention relates to reels adapted to the use of extension lights or for other suitable purposes, and the objects of my improvements are to provide means for automatically adjusting the reel to different horizontal angles corresponding to the direction of the light therefrom; to provide means for automatically locking the reel with the light at predetermined distances therefrom; to provide a guide for automatically turning the reel in different horizontal angles and also for properly directing the winding of the wire cord thereon, and to provide simple and durable construction and assemblage of the various members for securing facility of operation and efficiency of action. These and other objects may be attained in the following described manner as embodied in the claims and illustrated in the accompanying drawings, in which:

Figure 1 is an end elevation with parts broken away of a reel embodying my improvements; Fig. 2 a front elevation with parts broken away and parts in vertical diametrical section, and Fig. 3 a diametrical section of the swivel showing the frictional contact points in the electric circuit.

In the drawings 1 represents a bracket adapted to be secured at a fixed point and provided with a depending journal 2 whereon the sleeve 3 is swiveled and provided with the depending legs 4 and 5. The axle 6 is secured in said legs with the hollow drum 7 rotatively mounted thereon. Said drum is preferably formed with sheet metal heads having annular shoulders 8 near their periphery whereon the metal band 9 may be secured and the heads clamped together by means of bolts 11 to form the annular channel 12 for the winding of the electric light wire 13 therein.

The open guide 14 formed preferably of resilient wire and secured to the legs 4 and 5 of the yoke is located adjacent to the front face of the drum and curved in an arc concentric therewith. A stop 15 adjustably secured on the wire cord 13 by contact with the guide controls the relative lengths of the winding and depending portions of the cord to which the lamp 16 may be connected.

The coiled spring 17 located within the drum has one end connected with one of the clamping bolts 11 and the other end secured to the stationary axle 6 by means of the pin 18.

The bar 19, provided at one end with an inwardly projecting stop 21, is secured to the leg 4 and the gravity latch 22 pivotally secured at one end to the opposite end of said bar is formed with a projection 23 to detachably engage with said stop for limiting its descent, and with an inclined notch or open slot 24 adapted to automatically engage with either of the pins 25 which project at intervals from the adjacent end of the drum.

The insulated electric wires A and B may be connected with an electric light circuit and extended through the depending journal to the respective insulated circular terminals 28 and 29 which are secured to the said journal by means of the screw 31. Annular terminals 32 and 33 each formed with an internal groove 34 for movably engaging with the corresponding terminals 28 and 29 are connected with the corresponding wires C and D which are connected to the corresponding disk terminals 35 and 36 secured to the stationary axle 6. Annular terminals 37 and 38 rotatively mounted on the corresponding disk terminals 35 and 36 and free to turn with the drum are each formed with a radial arm 39 which is provided with a binding post 41. Wires E and F are extended from said respective posts through openings 42 and 43 in the corresponding end walls and the face of the drum and after being wound the desired number of times around the drum are thence extended through the guide 14 and stop 15 and terminate in the circuit with the lamp 16.

In operation, the lamp may be carried by the operator in any horizontal direction for unwinding the wire from the reel to the desired extent. The swivel will permit the drum to automatically turn with the guide in the direction of the extended wire. By relaxing the extended wire slowly the exertion of the spring will move one of the pins thereon into automatic engagement with the inclined notch in the gravity latch and lock it against further exertion of the spring. A short pull on the wire will turn the drum in a forward direction, for disengaging the pin from the latch when the drum may be turned at sufficient speed under the action

of the spring in rewinding the wire so that the pins will pass the notch in the latch without becoming engaged therewith.

In rewinding the wire on the drum the resilient guide will yield sufficiently under a sudden contact therewith of the stop on the wire to prevent injury to the lamp. Owing to the frictional terminals in the swivel and also those concentric with the axle, the drum 10 may be turned in either direction in different horizontal angles and also rotated in either of opposite directions without breaking the properly insulated lamp circuit.

The device is peculiarly adapted for use 15 in garages and may be applied in convenient use elsewhere.

Having fully described my improvements what I claim as my invention and desire to secure by Letters Patent of the United 20 States is:

1. An extension light reel comprising a yoke swiveled at a fixed point, a gravity latch pivotally secured thereto and formed with an inclined open slot, a drum journaled 25 in the yoke and provided with a stop, a spring for turning the drum with the stop into detachable engagement with the slot in the latch, wires wound on the drum by the action of the spring and provided with a 30 lamp, said wires with the lamp being in circuit with the source of an electric current and provided with swiveled terminals concentric with the yoke and with the drum, a guide secured to the yoke and arranged to 35 direct the wires toward the drum, and a stop adjustably secured on the wires and movable thereby into contact with the guide for regulating as desired the length of the pendant portion of the wires with the lamp.
2. An extension light reel comprising a yoke swiveled at a fixed point to turn in a horizontal plane, a hollow drum journaled in the yoke to turn in a vertical plane, a coiled spring located within the drum and

arranged to turn it in one direction, a lamp, 45 electric wires communicating with a source of current and provided with swiveled terminals concentric with the yoke and also with the drum, said wires being wound around the drum and terminating in circuit with the lamp, a resilient guide for the wires secured on the yoke and extended in front of the drum, a stop adjustably secured on the wires adapted to contact therewith for limiting the length of the portion 50 of said wires to be wound on the drum, a stop carried by the drum and a gravity latch pivotally secured to the yoke for automatically engaging therewith for discontinuing the rotation of the drum under the 55 exertion of the spring.

3. An extension light reel having in combination, a yoke adapted to be secured at a fixed point, a gravity latch pivotally secured thereto and formed with an inclined open 60 slot, a drum journaled in the yoke and provided with a stop, a spring arranged to turn the drum with the stop into detachable engagement with the slot in the latch, wires provided with a lamp and wound on the 65 drum by its action under the exertion of the spring, said wires with the lamp being in circuit with an electric current and provided with frictional terminals concentric with the axis of the drum, a guide secured 70 at a fixed point in relation to the drum and arranged to properly direct the wires toward the drum during the winding thereof, and a stop adjustably secured on the wires and movable thereby into contact with the 75 guide for regulating as desired the length of the pendent portion of the wires with the lamp.

ADAM HEIM.
